DESIGN FOR A STOP AND TAIL LAMP LENS

Samuel M. Dover, Chicago, Ill.

Application July 20, 1935, Serial No. 57,751

Term of patent 14 years

To all whom it may concern:

Be it known that I, Samuel M. Dover, a citizen of the United States, residing at Chicago, in the county of Cook and State of Illinois, have invented a new, original, and ornamental Design for a Stop and Tail Lamp Lens, of which the following is a specification, reference being had to the accompanying drawing, forming a part thereof.

In the drawing:

Figure 1 is a plan view of a stop and tail lamp lens embodying my novel design;

Figure 2 is an edge view thereof, and
Figure 3 is a section taken along the line 3—3
of Figure 1.

I claim:

The ornamental design for a stop and tail lamp lens substantially as shown.

Signed at Chicago, in the county of Cook and State of Illinois, this 18th day of July, 1935.

SAMUEL M. DOVER.
